UNITED STATES PATENT OFFICE.

HARRY C. SANDUSKY, OF NEWCASTLE, INDIANA.

RAIL-JOINT.

No. 899,190.

Specification of Letters Patent. Patented Sept. 22, 1908.

Application filed August 13, 1907. Serial No. 388,409.

To all whom it may concern:

Be it known that I, HARRY C. SANDUSKY, citizen of the United States, residing at Newcastle, in the county of Henry and State of Indiana, have invented certain new and useful Improvements in Rail-Joints, of which the following is a specification.

The present invention relates to improvements in rail joints and aims to provide a novel device of this character which will hold the rail ends rigidly in alinement with each other, thereby preventing the extremities of the rails from becoming battered and eliminating to a great extent the noise and jar incident to the passage of rolling stock over the joint.

A further object of the invention is to design a rail joint which is peculiarly formed so that the clamping members will hold the rail ends securely in position regardless of whether or not the bolts have worked loose.

The invention also contemplates a joint construction which will save considerable time and labor in railroad construction work since after the joint device has been placed in position the work train can pass over the same and the bolts can be inserted afterwards without any inconvenience.

For a full description of the invention and the merits thereof and also to acquire a knowledge of the details of construction and the means for effecting the result, reference is to be had to the following description and accompanying drawings, in which:

Figure 1 is a perspective view of a rail joint embodying the invention. Fig. 2 is a transverse sectional view through the same. Fig. 3 is a similar view showing the wings swung outwardly into the position assumed when applying the joint device to the rails.

Corresponding and like parts are referred to in the following description and indicated in all the views of the drawings by the same reference characters.

Specifically describing the present embodiment of the invention the numeral 1 designates the base plate which fits under the rails 2 and is provided along its opposite longitudinal edges with the upturned portions 3 formed with the inwardly facing grooves or sockets 4. It may also be observed that the upper face of the base plate 1 is inclined downwardly in opposite directions from the central portion thereof as indicated at 5. A pair of wings 6 are hinged to opposite edges of the base plate 1 and engage the opposite

sides of the rails 2. Each of these wings 6 is formed along one of its longitudinal edges with an enlargement or rib 7 fitting loosely within the respective sockets 4. In the preferred construction the mouths of the said sockets 4 are of less width than the sockets themselves and the ribs fit accurately within the sockets, thereby holding the wings against lateral displacement and necessitating that the same be placed in position by sliding the enlargement 7 into the sockets 4 from one end of the baseplate 1. Each of these wings 6 comprises an arm 8 designed to fit under the rails 2 and an arm 9 designed to engage a side of the rails 2. It will be observed that these arms 9 are each formed with an approximately horizontal portion designed to fit over the basal flange of the rails, and an approximately vertical portion 75 designed to fit against the web portion of the rails. When applying the joint the base plate 1 is placed in position upon the ties and the wings 6 swung outwardly as indicated in Fig. 3. The rails 2 are then moved downwardly into position, the basal flanges of the rails entering the recess between the two arms of each of the wings. As the rails 2 are lowered into position the arms 8 of the wings swing downwardly against the inclined 80 faces 5 of the base 1 while the arms 9 move inwardly against opposite sides of the rails. In order to prevent binding of the various members when thus applying the joint depressions 10 are formed in the horizontal 90 portions of the arms 9, the said depressions constituting a clearance space for the basal flanges of the rails 2. It will also be observed that the upper face of each of the arms 8 is formed with a slight depression 11; this construction resulting in causing the rails to press downwardly upon the extremities of the arms 8 and thereby swinging the wings 6 inwardly into a secure engagement with the opposite sides of the rails. The usual bolts 12 may be utilized for holding the two wings 6 in an operative position, but it will be readily apparent that any weight applied to the rails will tend to move the wings inwardly and hold the rails rigidly in alinement with each other regardless of whether or not the bolts are tight. Corresponding openings are formed in the base plate 1 and in the wings 6 through which the spikes 13 are driven by means of which the device is secured to the ties, the said spikes also serving to hold the wings in position.

It will be particularly noted that the base of my improved rail joint will serve as a tie plate, preventing the rails from cutting into soft ties.

Having thus described the invention, what is claimed as new is:

1. In a rail joint, the combination of a base provided upon opposite sides with sockets having the mouths thereof contracted, and wings formed with enlargements designed to be slipped longitudinally within the sockets but held against lateral displacement therefrom, each of the said wings comprising an arm designed to fit under the rails, and a second arm designed to engage the side of the same.

2. In a rail joint, the combination of a base which is inclined downwardly in opposite directions from the central portion thereof, and a pair of wings loosely connected to opposite longitudinal sides of the base, each

of the wings comprising a pair of arms one of which is designed to rest upon the corresponding downwardly inclined portion of the base and to fit under the rails while the opposite arm is designed to engage a side of the rails.

3. In a rail joint, the combination of a base, and wings hinged to opposite sides of the base, each of the wings comprising an arm designed to fit under the rails and formed with a depression tending to cause the weight of the rails to bear against the extremities of the said arm, and a second arm designed to engage the sides of the rails. 35 25

In testimony whereof I affix my signature in presence of two witnesses.

HARRY C. SANDUSKY. [L. S.]
